UNITED STATES PATENT OFFICE

WALTER DÄLLENBACH, OF ZURICH, SWITZERLAND

VACUUM DISCHARGE VESSEL

Application filed February 24, 1927, Serial No. 170,505, and in Switzerland March 4, 1926.

My invention relates to vacuum discharge vessels of metal and has for its particular object to improve the leading-in connections.

In view of the high tension existing between the vessel and the conductors discharges occur which will destroy the insulation resulting in leakage or short-circuits. Such discharges occur even at lower tensions, if the gas-pressure is increased, causing disturbances especially where gases or metal vapors participate in conveying current.

The dangerous discharges occur especially at the places where the insulating material touches conducting portions, and the present invention aims to provide means for guarding against such discharges.

As the insulator separates conducting parts of different electric voltage, there takes place across the surface of the insulator a drop of potential, which at that portion of the surface adjoining the rarefied gas will cause discharges. The first consideration, therefore, is to restrict this drop of potential to a narrow zone which is small as compared with the mean free distance travelled by the electrons in the rarefied gas. This one can accomplish by covering the side of the insulator directed toward the vacuum with conducting parts slightly spaced apart, some of which conducting parts have the potential of the conductor, while others have the potential of the metal vessel. Without touching each other, the said conducting parts of different potential are arranged opposite to each other in a narrow zone. By such an arrangement the discharges are made much more difficult, the discharges being restricted in the gas space to a narrow zone in the direction of the electric field lines, so that a collision of the particles of the charge with the gas particles is not likely to occur.

However, in many cases, this arrangement is not sufficient. The insulating material generally has a high emission of ions and electrons, which share in the discharge and are apt to considerably reduce the discharge tension. But this emission of ions and electrons can take place only, if the electric charges can be maintained. Because of the poor electric conductivity, this is possible only at those

places where the insulator directly adjoins the conducting parts, for the ions and electrons which the surface of the insulator emits into the gas space, can be supplied at those points of contact by the conducting parts. 55 This discovery has led to the present invention. The zone, upon which the drop of potential is concentrated must be taken away from the points of contact of the insulating material with conducting parts in the vacuum. Of course, the distance of the zone from such points of contacts must be sufficiently great and must be at least several times greater than the width of the zone, so that in spite of their high emission of ions and electrons, 60 they can not contribute to a discharge in the rarefied gas.

In the first place, this expedient is applied to the insulator whereby the sealed leading-in of the conductor is effected. In this way, the surface of the insulator insofar as it adjoins the rarefied gas shall be protected. Moreover, insulating bodies can be provided which lie entirely in the vacuum, and these must also be protected, if the introduction of the current shall be able to withstand higher tensions. 75

Where very high tensions are present, it may become necessary to concentrate the drop in potential instead of one zone only, upon several narrow zones, which zones must be mutually separated by spaces being a multiple of the width of the zone, since an eventual discharge in one zone must not interfere with the discharge tension in the others. Moreover, all said zones must have a sufficiently great distance from all the points of contact of the insulating material with the conducting parts, and these distances should be at least a multiple of the width of the zone. 80 85 90

In the drawing illustrating in a sectional view one embodiment of my invention:

G is the wall of the vacuum discharge vessel of metal, E is the electrode, L the conductor which carries the electric current and J 95 the cylindrical insulator. Its surface where it adjoins the vacuum is substantially covered by two metal projections F and F', forming with J a narrow gap UVS'. A similar gap is provided between F and F'. Since F is 100

- electrically connected with the wall of the metal vessel and F' with the electrode, the drop in potential between G and E is concentrated on a narrow zone on the surface of the insulator at V. The width of said zone shall correspond in size to or shall be small as compared with the length of the paths travelled by the electrons in the rarefied gas.
- 5 The zone at V is moreover removed about a multiple of its width from the points of contact X and X' between the insulator and the conducting parts in the vacuum. Furthermore, by this arrangement, the insulating material is protected against the discharges
- 10 which normally start from the active surface of the electrode, for the particles of the charge must diffuse through the narrow gap VS, before they can reach the surface of the insulator.
- 15 20 The insulator J need not serve as a sealing medium for the vacuum as shown in the drawing, for it might be located entirely in the vacuum and be used, for example, as a mechanical support.

25 I claim:

In a vacuum discharge vessel of metal for containing a rarefied fluid, the combination of an electrode, an insulator sealing said electrode in said vessel and slightly spaced conducting parts covering a portion of the surface of said insulator within the vessel, one of said parts being electrically connected with said vessel and another of said parts with said electrode, said conducting parts forming a narrow gap in which the drop in potential between said vessel and said electrode is to be concentrated, said gap being located from the points of contact of said insulator and conducting parts in the vacuum at a distance forming a multiple of its width, the latter being small compared with the path traveled by the electrons in the rarefied fluid.

Signed at Berlin, Germany, this 9th day of February 1927.
